UNITED STATES PATENT OFFICE.

JAMES W. DURHAM, OF TIPTON, INDIANA.

GATE HINGE.

Application filed April 17, 1922. Serial No. 553,331.

To all whom it may concern:

Be it known that I, JAMES W. DURHAM, a citizen of the United States, residing at Tipton, in the county of Tipton and State 5 of Indiana, have invented certain new and useful Improvements in Gate Hinges, of which the following is a specification.

The present invention relates to improvements in gate hinges.

10 The object of the present invention is to improve the construction of gate hinges and to provide a simple, inexpensive, and efficient one of great strength and durability, adapted to be readily applied to gate posts 15 of different sizes and capable of being securely attached thereto.

Another important object of the invention is to provide a clamping device for holding the hinge pintle which is formed in 20 a plurality of adjustable sections so as to be engageable about different sized and different shaped fence posts.

With these and other objects in view, the invention consists in the construction and 25 novel combination of parts hereinafter fully described, illustrated in the accompanying drawings and pointed out in the claims hereto appended, it being understood that various changes in the form, proportion, size 30 and minor details of construction within the scope of the claims, may be resorted to without departing from the spirit or sacrificing any of the advantages of the invention.

35 In the drawing:—

Figure 1 is a perspective of the hinge embodying my invention and shown applied to portions of a gate and a post.

Figure 2 is an elevation of the pintle and 40 clamp thereof,

Figure 3 is a section taken on the line 3—3 of Figure 2 looking in the direction of the arrow,

Figure 4 is a detailed perspective of an 45 auxiliary device used in conjunction with the clamp, and

Figure 5 is a plan view showing the auxiliary member and the clamp assembled about a gate post.

50 Referring to the drawing in detail it will be seen that the gate 1 of conventional construction is disposed adjacent the fence post 2 which is circular in cross section. A strap hinge member 3 is securely attached to the gate 1 and terminates beyond its hinged side 55 in a loop 4 which is received upon the ver-

tical portion 5 of the right-angled shape pintle 6.

The clamp support for the pintle 6 is formed from a plurality of sections. Two 60 of these sections 8 are hinged together as at 9 and are provided with longitudinally extending slots 10 having a plurality of notches 11 communicating therewith at its upper edge for receiving the headed rivets 65 12 which are mounted on the auxiliary sections 13. These auxiliary sections 13 terminate in apertured ears 14 for receiving the bolt 15 having thereon a nut 16. There are preferably two headed rivets or pins 12 on 70 each of the auxiliary sections 13 and it will be readily understood from an inspection of the drawing that these auxiliary sections 13 may be adjusted in relation to the hinged sections 8 so that the clamp device may be 75 disposed about fence posts of varying sizes. It is to be understood also that the angled shaped pintle 6 is integrally formed or otherwise attached to one of the hinged sections 8.

80 In Figures 4 and 5 I have disclosed an auxiliary filling member adapted to be used with the clamp device when the same is disposed about a fence post of square formation or the like such as shown in Figure 5 85 and indicated at 18. This auxiliary filling device comprises a curved channel bar 19 which has projecting from its intermediate portion a filling lug 20 substantially U-shaped in formation. The adjacent hinged 90 member 8 and auxiliary member 13 are disposed in the channel of the channel bar 10 while the lug 20 engages one of the faces of the post 18 whereby a firm grip may be had upon the post since the clamp will bear 95 thereon in five different places as disclosed in Figure 5. Of course, it is readily understood that as many of these auxiliary filling devices may be used as found necessary or desirable, the illustration in Figure 5 being 100 given only as one example of its use.

Having thus described my invention what I claim as new is:—

1. A clamp of the class described including in combination a pair of hinged sections, 105 a pair of auxiliary sections, one pair of said sections provided with longitudinally extending slots having marginal notches communicating therewith, and pins extending from the other pair of sections adapted to 110 penetrate said slots so as to be movable therein for engagement with said notches.

2. A clamp of the class described including in combination a pair of hinged sections, a pair of auxiliary sections, one pair of said sections provided with longitudinally extending slots having marginal notches communicating therewith, pins extending from the other pair of sections adapted to penetrate said slots so as to be movable therein for engagement with said notches, and a 10 pintle mounted on one of the sections, and a hinged member associated therewith.

3. A clamp of the class described including in combination a pair of hinged jaws, each jaw comprising a main section and an 15 auxiliary section, one of said sections provided with a slot having notches communicating therewith, a pin extending from

the other section and piercing said slot for engagement with the notches, and means for holding the sections together in the manner 20 and for the purpose specified.

4. In combination, a gate hinge member, a post hinge member associated therewith, a clamp for supporting the latter, a curved channel bar engageable with the clamp, and 25 a lug projecting from the inner periphery of the curved bar in the manner and for the purpose specified.

In testimony whereof I affix my signature in presence of two witnesses.

JAMES W. DURHAM.
